UNITED STATES PATENT OFFICE.

WILLIAM C. BARNEY, OF NEW YORK, N. Y., ASSIGNOR TO JOSIAH C. REIFF,
OF SAME PLACE.

TELEPHONE-RECEIVER.

SPECIFICATION forming part of Letters Patent No. 357,360, dated February 8, 1887.

Application filed January 18, 1886. Serial No. 188,814. (No model.)

To all whom it may concern:

Be it known that I, WILLIAM CHASE BARNEY, of the city and State of New York, have invented an Improvement in Telephone-
receivers, of which the following is a specification.

This invention relates to telephone-receivers known as "electro-magnetic" receivers.

In order to avoid the sounds which are emitted by a plate of iron when secured around its edge and submitted to the action of a magnet, I use for an armature a short thick piece of iron. This mass is secured to a very light elastic support, in order that the support may offer very little resistance to the attraction of the magnet. I use for a tympan or sounding-board a thin sheet of wood, card-board, celluloid, glass, horn, ivory, bone, cork, mica, vulcanite, brass, or equivalent material. I find that when the tympan is inclosed in a case or sounding-box the vibrations of the tympan produced by the varying attractive force of the magnet are injuriously affected. I find, also, that the passage of air-waves through a tube are more or less injuriously affected by the vibrations of the sides of the tube. Therefore my tympan is secured at its edge to a rigid support attached to the magnet, and there is no substance whatever between the vibratory part of the tympan and the ear of the listener. Sometimes a permanent magnet having a coil surrounding it from end to end may be used, and in order to increase the magnetic force of the pole of the magnet in front of the armature I place a mass of soft iron against the other pole of the magnet.

The armature is made of soft iron in the form of a short thick mass of iron of about the same diameter as the end of the magnet, and its length is about equal to its diameter. This armature is attached to a thin piece of wood, whalebone, vulcanite, brass, or equivalent material. The ends of this armature-holder lie loosely in cavities made in a support attached to the case of the magnet. On the opposite side of the material supporting the armature is a short spur, against which is held a tympan, of wood or equivalent material, clamped around its edge between two rings attached to the case of the magnet. The tympan is protected from coming into contact with the ear

by a ring supported by several projections from the ring. The holder to which the armature is attached may be a straight piece, or may have the form of a cross having three or four arms. The ends of the arms of the cross may be curved, so that they will form, as it were, legs to support the armature, their ends to rest loosely in cavities made in the ring attached to the case of the magnet.

In order to put the tympan out of condition to produce its particular scale of harmonic sounds, I pierce it with holes irregularly placed and outside the portion thereof lying over the core of the magnet, thus leaving it to reproduce the words of the speaker without alteration in quality or tone or in any other respect.

In the drawings, Figure 1 is a longitudinal section of the telephonic receiver. Fig. 2 is a separate elevation and side view of the armature and support. Fig. 3 is a detached edge view and side view section of the bird's-eye-maple tympan with holes in it. Fig. 4 is an end view of the instrument. Fig. 5 is an edge view, and Fig. 6 is a side view, of the armature-support in the form of a cross.

A represents the core of the magnet, which core may be permanently magnetized, and B denotes the helix or coils of the same.

In order to intensify the action of one end of the magnet, the mass of soft iron C is attached to the other pole thereof. Opposite the other pole thereof is the armature D, in the form of a short thick piece of iron, as aforesaid, that is fastened to the elastic support E, which is made as before stated, and sustains the armature in proximity to the pole of the magnet; but the support is free to move as the armature is vibrated by the variations in the magnetism. At the other side of the armature-support E there is a projection, F, that rests against the tympan G. This tympan will operate with the other parts, heretofore named, when made of any suitable material; but I find that a veneer of bird's-eye maple is the best, because it has no tone of its own when vibrating, in consequence of the knotty nature of the wood.

The edges of the tympan G are clamped between the rings H so as to be properly held, and one of these rings is formed upon or con-

nected with the handle portion of the instrument, that is composed of a case surrounding the electro-magnet. In the casing below the ring H several openings, O, are made, so that the air is not confined upon either side of the tympan. One way of making such openings is to form the upper part of the case with lugs or arms, the spaces between which form the openings when the ring H is in position. The ring I may be pressed against the side of the head and the ear; but I prefer to use projections L, that extend out from the ring I and limit the approach of the instrument to the ear.

15 The coil on the electro-magnet may extend from end to end thereof.

The holes in the tympan are shown in Figs. 3 and 4.

I claim as my invention—

20 1. The combination, in a telephonic receiver, with an electro-magnet, of an armature consisting of a short thick piece of iron, and a free elastic support for the same, substantially as specified.

25 2. The combination, in a telephonic receiver, with an electro-magnet having a mass of soft iron attached to one of its poles, of an armature in front of the other pole consisting of a short thick piece of iron, and a support, to which the same is attached, substantially as specified.

30 3. The combination of an armature capable of inductive action with a permanent magnet covered with a coil throughout its entire length, having a mass of soft iron in close contact with one end thereof, substantially as specified.

35 4. The combination, in a telephonic receiver, of an armature consisting of a short thick

piece of iron, and an elastic support, to which the armature is attached, and a permanent magnet covered with a coil throughout its entire length, and a mass of soft iron in close contact with one end thereof, substantially as set forth.

5. The combination, with an electro-magnet and armature composed of a short thick piece of iron, of a tympan formed of a thin plate of wood, card-board, vulcanite, mica, brass, or equivalent material, substantially as set forth.

6. In a telephone receiver, the combination, with a magnet and an armature, of an independent tympan having several holes pierced irregularly therethrough outside of the portion thereof lying over the core of the magnet, as and for the purposes set forth.

7. The combination, in a telephonic receiver having a magnet, an armature, and a tympan, of an open support for the armature and tympan, so that the air is not confined at either side of the tympan, substantially as specified.

8. The combination, with the magnet and armature, in a telephonic receiver, of a tympan of bird's-eye maple, for the purposes set forth.

9. The combination, with a permanent magnet having coil's around the end or ends of said magnet, of an armature consisting of a short thick piece of iron attached to a free elastic support, substantially as specified.

Signed by me this 9th day of January, A. D. 1886.

W. C. BARNEY.
